UNITED STATES PATENT OFFICE.

FREDERICK F. ZAVATKAY, OF WINSTED, CONNECTICUT.

ICE CUTTER.

1,412,500.

Specification of Letters Patent. Patented Apr. 11, 1922.

Application filed May 31, 1921. Serial No. 473,899.

To all whom it may concern:

Be it known that I, FREDERICK F. ZAVATKAY, a citizen of the United States, residing at Winsted, in the county of Litchfield and 5 State of Connecticut, have invented a new and useful Improvement in Ice Cutters; and I do hereby declare the following, when taken in connection with the accompanying drawings and the characters of reference 10 marked thereon, to be a full, clear, and exact description of the same, and which said drawings constitute part of this application, and represent, in—

Fig. 1 a front view of an ice cutter constructed in accordance with my invention.

Fig. 2 a sectional view on the line 2—2 of Fig. 1.

Fig. 3 a vertical sectional view on the line 3—3 of Figure 2.

Fig. 4 a perspective view of one of the cutters detached.

Fig. 5 a plan view of one of the filler-blocks detached.

Fig. 6 an end view of the same.

Fig. 7 an inside view of one of the outer filler-blocks detached.

Fig. 8 an end view of the same.

Fig. 9 an inside view of the cushion-block between the channel and front plate of the 30 plow detached.

Fig. 10 an end view of the same.

This invention relates to improvement in ice cutters and particularly for attachment to snowplows of railway engines, the 35 object being to provide a device which may be used in connection with snowplows of usual construction designed to be raised or lowered to meet conditions required by depth of ice to be cut, and which will have a sawing or shearing effect on the ice, so that it 40 will operate with less friction and permit the plow to be run at a comparatively high rate of speed, and the invention consists in the construction and arrangement of parts 45 as will be hereinafter described and particularly recited in the claims.

In carrying out my invention, I employ two bases in the form of channel-irons 15 and 16 which are attached to the front plates 50 17 of a vertically adjustable snowplow adapted to be attached to the front of a railway plow, the plates being arranged at

an angle, so as to form a wedge-shaped plow. Between the channel and the plates 17 is a cushion-block 18 and secured to the 55 face of the channel-irons are a series of cutters 19 having forwardly-projecting cutting-edges 20 formed at their outer ends with beveled saw-teeth 21. Eight cutters are usually required for each side of the plow 60 and the cutters are so arranged on the channel that the cutting-edge is at an angle of about thirty degrees. These cutters are separated from each other by spacing-lugs 22 projecting upward from a metal filler-block 23 located within the channel-irons below the cutters, so as to provide a rigid support therefor. In front of the cutters are blocks 24 of iron or armored wood. 65

The cutters are bolted to the channel-iron; 70 the blocks 24 also bolted to the channel-iron and all bolted to the front plate of the plow, so as to form a rigid construction necessary to stand the strain imposed upon it when cutting ice under pressure of a high-powered engine. By arranging the cutters as 75 shown they have a sawing or shearing effect on the ice, resulting in easy operation, due to lack of friction, so that the plow may be run at a comparatively high rate of speed. 80

This device will not only remove ordinary snow from the rails but will cut away heavy coatings of ice from the top of the rail, inside the rails, and for a sufficient distance outside the rails to a depth of three 85 inches below the top of the rail.

I claim:

1. An ice cutter comprising bases adapted to be secured to the front plate of a snowplow, a series of flat cutters secured to 90 the outer face of said bases, said cutters having forwardly-projecting cutting-edges provided with a plurality of beveled teeth.

2. An ice cutter comprising channel-irons adapted to be secured to the front plate of a snowplow, blocks between said channel and front plate, a series of cutters secured to the outer face of the channel-iron, and provided with forwardly-projecting cutting-edges, blocks within said channels below said 100 cutters and provided with spacers extending outward between the cutters.

3. An ice cutter comprising channel-irons adapted to be secured to the front plate of a

snowplow, cutters secured to the outer face of said channels, said cutters having forwardly- and downwardly-projecting cutting-edges terminating in beveled teeth, filler-blocks in said channels beneath said cutters and filler-blocks located forward of said cutters and providing firm supports therefor.

In testimony whereof, I have signed this specification in the presence of two subscribing witnesses.

FREDERICK F. ZAVATKAY.
